LOCK SEALING MEANS

Francis Thornton Smith and Charles B. Polhemus, San Jose, Calif.

Application April 16, 1934, Serial No. 720,798

5 Claims. (Cl. 70—8)

The present invention relates particularly to means for securing a lock, such as commonly used upon automobile doors and the like, against opening by means of the key provided therefor.

It is the principal object of the invention to provide a means whereby a properly authorized and equipped official may render the lock on a vehicle inoperative until restored to an operative condition by him or another authorized individual.

It is also an object to provide a device of the character indicated that may be quickly and easily applied and removed from a lock, that is simple in form and construction, economical to manufacture, that will permit the quick and easy attachment of a tag thereto, that will be positive in operation, and highly efficient in its practical application.

In the drawing:

Figure 1 is a perspective illustration of a device embodying our invention.

Figure 2 is a sectional view through a device embodying another form of the invention.

Figure 3 is a sectional view on line 3—3, Figure 4.

Figure 4 is a side elevation of a tool used in applying the device embodying our invention.

In the form of the invention shown in Figure 1 the body of the device is formed of lead or any suitable soft alloy or composition. This body portion consists of a head portion 1 having a flat face 2 adapted to seat against the face of the lock on which it is to be used and covering the key slot formed therein. On the face 2 is formed a radially disposed triangular boss 3 adapted to enter the key slot indicated in dotted lines at 4.

The portion 1 has a conical rear face 5 terminating in a cylindrical portion 6, and a hole 7 is formed in the device and passes axially therethrough as shown.

At 8 is shown a steel wire having one end bent back upon itself as at 9 to form an angle 10 of approximately eighty-nine degrees. This wire 8 passes entirely through the hole 7 and has a slightly crimped body portion and an end 11 formed into a loop and then into a hook at 12 to engage the body portion of the wire.

In applying this form of the device the bent end 9 is inserted in the key slot of the lock and brought into engagement with any available interior part. The part 1—7 is then moved up into contact with the face of the lock and with the part 3 engaging the key slot, after which the cylindrical portion 6 is pinched down upon

the wire 8. The wire 8 is crimped throughout the major portion of its length so that when the metal is pinched upon it the element 1—7 will be securely held against movement relative thereto.

In fastening the element 1—7 in place a special tool is used. This tool comprises a pair of pliers 13 having jaws terminating in opposed cutting edges as 14. The portion of the jaws between the cutting edges and the pivot are provided with bevelled opposing sides as at 15 and 16, the bevelled faces diverging toward the edge of the tool that is placed closest to the lock when the tool is applied.

In using the tool it is placed crosswise of the part 6 and actuated in the usual manner. But since the edge 17 of the jaws acts upon the metal first it follows that the cylinder 6 is broken down first where the edge 17 contacts it, and this portion of the cylinder being crushed into intimate engagement with the crimped wire effectively prevents outward movement of the part 1—7 thereon. As the crushing operation is continued and the inner portion of the cylinder is broken down the metal is caused to flow toward the lock, consequently the part 1 is forced mechanically into intimate engagement with the face of the lock. Since the parts are held against a rotative movement by the engagement of boss 3 with the key slot it follows that the device cannot be easily removed and the key slot is effectually blocked against insertion of the key therein.

In removing the locking device the tool 13 is used. In this case the cutting edges 14 are used to split the device longitudinally after which it may be moved away from contact with the lock and the wire removed.

This device is primarily intended to be applied by an officer to a vehicle that has occupied a given parking space for a longer period than that permitted by law. When the device has been applied, therefore, the hook 12 is unfastened and a ticket 18 slipped thereon, after which the hook is again engaged. By this means the official ticket is quickly attached without interfering with the effectiveness of the device.

In the other embodiment of the invention as shown in Figure 2 the part or body of the device 19 is similar to the corresponding part of the embodiment first disclosed, but the boss 3 is omitted and two holes as 20—21 are formed therein through which two wires as 22—23 are passed as shown. The wire 22 is similar to wire 8 in conformation, but wire 23 has no hook on 55

its inner end. When the free ends of these two wires are inserted in the key slot as hereinbefore described and the part 19 crushed with a suitable tool, the web 24 between the two holes 5 20—21 breaks down before the thicker side walls and spreads laterally, thereby forcing the wires apart so that the wire 23 bears against the wall of the slot opposite to the wall against which wire 22 bears. These wires of course engage the projecting parts in the lock and cannot be turned.

It is to be understood, of course, that while we have herein shown and described but two specific embodiments of the invention, changes 15 in form, construction, and method of assembly and application, may be made within the scope of the appended claims.

We claim:

- 20 1. Means for sealing the key slot of a lock comprising, an element formed to enter the key slot of a lock and hook upon a lock part, and a malleable material mounted upon the element and movable into engagement with the face of the lock.
- 25 2. Means for sealing the key slot of a lock comprising, an element formed to enter the key slot and hook upon a lock part and having an irregular body portion, and a body of material that will yield under pressure mounted upon the

irregular portion of said element and movable into engagement with the lock face.

3. Means for sealing the key slot of a lock comprising, a wire having one end bent to form a hook and the other end bent to form a loop with the terminal portion of said end detachably engaging the body of the wire, and the body of the wire having a deformed section, and a body of malleable material adjustably mounted on said wire and having a portion formed to enter 10 the key slot to prevent rotation of the body relative to the lock.

4. Means for sealing the key slot of a lock comprising a body of malleable material having holes formed therein and passing therethrough, 15 and a wire slidably engaging each hole, one wire having a hook formed on one end thereof and a loop on the other end thereof.

5. Means for sealing the key slot of a lock comprising, an element formed to enter the key 20 slot of a lock and hook upon a lock part, and a body of malleable material slidably associated with the element and movable into engagement with the face of the lock and provided with means adapted to enter the key slot to prevent 25 its rotation relative to the lock.
